UNITED STATES PATENT OFFICE.

GRANVILLE T. SHEPLEY, OF WEST GROTON, ASSIGNOR TO EDWIN H. SAMPSON, OF BOSTON, MASSACHUSETTS.

MACHINE FOR FORMING COUNTER-STIFFENERS.

SPECIFICATION forming part of Letters Patent No. 298,420, dated May 13, 1884.

Application filed March 31, 1884. (No model.)

To all whom it may concern:

Be it known that I, GRANVILLE T. SHEPLEY, of West Groton, in the county of Middlesex and State of Massachusetts, have invented a new and useful Improvement in Attachments for Counter-Machines, of which the following is a full, clear, concise, and exact description, reference being had to the drawings accompanying and forming a part hereof.

10 My invention relates to the machine for manufacturing boot or shoe counters patented to John R. Moffitt, and more fully described in Letters Patent No. 178,869, dated June 20, 1876; and it consists of an attachment, herein-after more fully described, adapted to be secured to the rolling mechanism of said machine, which consists, essentially, of concave and convex rolls, between which the flat blank is passed to produce what is known as a "clam-shell." By the use of my attachment the work of the operator is rendered easier and safer and the production of the machine increased.

25 In the drawings, Figure 1 is a front view of the rolls of the Moffitt machine with my improvement attached. Fig. 2 is a section on line *x x*, Fig. 1.

30 A is the convex "former," and B the correspondingly-concaved upper roll. The counter-blank is fed in between these rolls, and bent into a circular shape around the former A. As the operator feeds a blank in, it has been hitherto necessary for him to place his hand under the former A, seize the circular-shaped counter or blank while a portion of it was still in the nip of the rolls, hold it off the former, and, when it was free from the rolls, drop it into a basket below the machine. Unless the operator did this, the counter or blank would hug the former A and pass a second 35 time between it and the upper roll, B. To prevent this and free the operator from any care for the blank other than feeding it properly to the rolls, I have devised the simple con-

trivance shown in the drawings, and which I will now describe.

45 A metallic strip, C, bent in the form shown, to lie closely to the frame D of the machine and present as little obstruction as possible, is secured at E to the frame D. Near its lower end the strip C is bent so as to project at right angles to the frame D, parallel with the axis of the former A, and from the frame to a point in front of the former. This projecting end of the strip C is provided with a plate, F, cut concave at its inner edge, *b*, in order that it may be set close to or against the convex periphery of the former. The plate F is provided with parallel slots *a a* and set-screws, by which it is secured to the end of strip C, the slots *a a* admitting of the adjustment of 50 the plate relatively to the periphery of the former. As the blank passes around the former from the nip of the upper roll, it comes in contact with the plate F, and is freed from the former and drops into the inclined spout 55 H, whence it is conveyed to the basket or other receptacle placed to receive it.

55 What I claim is—

1. The herein described attachment, consisting of the strip C, secured to the frame at one 70 end, and at the other provided with the plate F, having its inner edge concaved to allow of its being set close to or against the convex periphery of the former, substantially as described.
2. In combination with the former A, the plate F and its support C, for the purposes and substantially as described.
3. The combination of former A, plate F, provided with slots *a a*, strip or arm C, and 75 spout H, substantially as described.

GRANVILLE T. SHEPLEY.
